Charles B. Harbin, Atlanta, Ga., assignor to Atlanta Metallic Casket Co., Atlanta, Ga., a corporation of Georgia

Application January 16, 1933. Serial No. 46,854

Term of patent 3½ years

To whom it may concern:

Be it known that I, CHARLES B. HARBIN, a citizen of the United States, and resident of Atlanta, county of Fulton and State of Georgia, have invented a new, original, and ornamental Design for Caskets, of which the following is a specification, reference being had to the accompanying drawing, forming a part thereof, and in which:

I claim

The ornamental design for a casket substantially as shown.

CHARLES B. HARBIN,
